US00D871041S

(12) **United States Design Patent** (10) **Patent No.:** **US D871,041 S**
Buck (45) **Date of Patent:** **** Dec. 31, 2019**

(54) **INSOLE**(71) Applicant: **PROTALUS LLC**, West Linn, OR (US)(72) Inventor: **Christopher Buck**, West Linn, OR (US)(73) Assignee: **PROTALUS LLC**, West Linn, OR (US)(***) Term: **15 Years**(21) Appl. No.: **29/653,417**(22) Filed: **Jun. 14, 2018****Related U.S. Application Data**

(63) Continuation of application No. 29/586,543, filed on Dec. 5, 2016, now Pat. No. Des. 820,573.

(51) **LOC (12) Cl.** ..... **02-04**(52) **U.S. Cl.**USPC ..... **D2/961**(58) **Field of Classification Search**

Primary Examiner — Elizabeth J Oswecki(74) *Attorney, Agent, or Firm* — Mark T. Vogelbacker; Eckert Seamans Cherin & Mellott, LLC(57) **CLAIM**

The ornamental design for an insole, as shown and described.

DESCRIPTION

FIG. 1 is a perspective view of an insole showing my new design;

FIG. 2 is another perspective view thereof;

FIG. 3 is a top plan view thereof;

FIG. 4 is a bottom plan view thereof;

FIG. 5 is a side elevation view thereof;

FIG. 6 is an opposite side elevation view thereof;

FIG. 7 is a front elevation view thereof; and,

FIG. 8 is a rear elevation view thereof.

The broken lines in the figures illustrate environmental structure only and form no part of the claimed design.
